UNITED STATES PATENT OFFICE.

JOSEPH H. CHAMP, OF CLEVELAND, OHIO.

TIRE-INFLATER.

SPECIFICATION forming part of Letters Patent No. 691,745, dated January 28, 1902.

Application filed July 16, 1900. Serial No. 23,705. (No model.)

To all whom it may concern:

Be it known that I, JOSEPH H. CHAMP, a citizen of the United States, and a resident of Cleveland, county of Cuyahoga, and State of Ohio, have invented a new and useful Improvement in Tire-Inflaters, of which the following is a specification, the principle of the invention being herein explained and the best mode in which I have contemplated applying that principle, so as to distinguish it from other inventions.

The object of the invention is to provide an improved tire-inflator, especial attention having been given to same in its fitness for use 15 as connected with coin-controlled apparatus.

The nature of the invention consists of the means hereinafter described, and particularly pointed out in the claims.

The annexed drawings and the following 20 description set forth in detail certain mechanism embodying the invention, such disclosed means constituting but one of various mechanical forms in which the principle of the invention may be used.

25 Figure I is a vertical transverse section through the casing of the machine, but without section through the inclosed mechanism. Fig. II is a front elevation of the mechanism inclosed by the casing and showing the latter 30 in vertical section at right angles to the section of the preceding figure. Fig. III is a view, taken like the immediately-preceding one, of a modified form of the casing-inclosed mechanism. Fig. IV is a detail top plan of 35 the handle mechanism connected with the duplicate valve mechanisms and of the coin-controlling mechanism. Fig. V is a front elevation of said members of the immediately-preceding figure, but having that portion of 40 the front casing which carries the handle removed. Fig. VI is a detail, partly in vertical section and partly in vertical side elevation, of one of the twin valve mechanisms shown in the immediately-preceding figure. Fig.

45 VII is a detail of a portion of the coin-controlling mechanism. Fig. VIII is a detail at right angles to the plane in which the immediately-preceding figure is taken. Fig. IX is a detail view, mainly in vertical section, of 50 the fluid connections of the expansion-cylinder shown in Fig. III.

The casing A may be of any suitable con-

struction, its purpose being to exclude the public from access to the inclosed mechanism and also to protect the latter from the 55 weather. It is preferably provided at its rear with a door a, whereby privileged access may be had to its interior. Two upright cylinders B B' are provided, the larger one, B, being a storage-cylinder of compressed carbonic-acid gas and the smaller one, B', being a measure-cylinder to permit a given limited volume of gas to be subject to draft upon insertion of a certain coin into the coin-slot. Cylinder B communicates by tube b with the 60 pressure-regulator c, having a gage-dial c', subject to conditions adapted to automatically cause gas from such storage-cylinder to pass under a predetermined pressure into the tube d. This tube d carries the fluid to the 65 bottom of the valve-cylinder e, wherein communication with the tube f, connected with the upper side portion of said cylinder, is controlled by a valve having a tendency to be maintained in raised position by a spring, 70 such raised position of the valve shutting off communication within the valve-chamber between said tubes d and f. This valve mechanism controls the induction of the fluid relatively to the measure-cylinder and is a duplicate of the valve mechanism, hereinafter referred to, which controls the eduction of the fluid relatively to the measure-cylinder, and the interior construction of each such valve mechanism is shown by the single view of 75 Fig. VI. Said tube f discharges into the lower portion of the measure-cylinder B', the upper portion of such measure-cylinder connecting with one extremity of a tube g, the opposite extremity of said tube g connecting with the 80 bottom of valve-cylinder h, such cylinder h being of construction and having an inclosed upwardly spring-pressed valve such as shown in Fig. VI, the upper side portion of such cylinder h connecting with tube i, 85 which latter connects with the tire-feed nozzle j, projecting out through the lower portion of the front wall of the casing A.

Each of the twin valve-cylinders e and h has a pivoted angular lever, whose under side 90 engages with the top of a valve-stem, each such pivotal lever being adapted to be depressed by a cam carried on the lower side of horizontal slide C, the opposite end portions

of the latter having free sliding movement in bearing-boxes *k*. Said lever, stem, and cam of the induction mechanism are respectively lettered, as *l m o*, while the corresponding members of the eduction mechanism are respectively lettered, as *l' m' o'*.

Rock-shaft *D* has a sleeve *E* threaded thereon and adjustably clamped thereto by a set-screw *p*, such sleeve having rigidly secured thereto a weighted arm *q*. The rock-shaft is further provided with a rigid arm *r*, adapted to work freely within a slot *s*, formed longitudinally in a horizontal plate *F*, located beneath the horizontal slide *C*. The rock-shaft is adapted to be operated by a handle *G*, which is suitably fitted in and projects outwardly from the central portion of the front wall of the casing.

A coin-slot *H* is in the front wall of the casing and connects with a coin-chute *L*, terminating above receptacle *t*. An additional chute *N* is located below the discharge end of plate *F*, and a cash-box *P* is located below the discharge end of such chute.

25 The slide *C* has its approximately middle portion provided with a transverse receptacle *t* of size adapted to receive a desired coin in a vertical plane above said plate *F*. Said coin-receptacle *t* has its lower central portion formed with an opening *v* of size suitable to permit arm *r* to work freely therein when there is no coin in receptacle *t*.

The construction of the foregoing members is such that when a coin has entered receptacle *t* it drops onto plate *F* and there remains as a barrier against the passage of arm *r* through opening *v*, so that when handle *G* is turned to the right arm *r* engages against the face of the coin, and the latter then serves as a mechanical member to cause slide *C* to be correspondingly moved to the right until the coin has reached a vertical plane to the right of plate *F*. The coin then being freed from support falls of its own gravity into chute *N* and is therefrom dropped into cash-box *P*.

In Fig. III is shown a modification wherein an upright cylinder *B*² is introduced in fluid connection between the pressure-regulator *c* and the induction-valve cylinder *e*. The purpose of such cylinder *B*² is to permit any cool and condensed carbonic-acid gas to warm and rarefy before being subjected to draft for tires. Such expansion-cylinder has its top provided with fluid connections, such as shown in Fig. IX. Tubes *f* and *g* in this instance are shown as each communicating with the top of the measure-cylinder *B'*.

The operation of the machine is as follows, 60 assuming certain members in position such as is shown in Fig. V: The bicyclist removes the cap from the nipple of his tire and places his wheel on the tire-feed nozzle *j*, with the opened nipple fitting in the open end of such 65 nozzle, the mouth of the latter being of size and shape adapted to effect substantially an air-tight joint with such open nipple of a wheel-

tire. The bicyclist then slips a suitable coin into slot *H*, whence the coin passes down chute *L* into coin-receptacle *t*. The bicyclist then turns handle *G* toward the right, causing arm *r* to throw slide *C* toward the right, thereby causing cam *o* to be disengaged from lever *l*, so as to permit stem *m* of the upwardly spring-pressed valve in cylinder *e* to rise, resulting in said valve rising and closing communication between tubes *d* and *f*, and simultaneously therewith cam *o'* depresses lever *l'*, which latter depresses stem *m'* of the upwardly spring-pressed valve in cylinder *h*, resulting in said valve lowering and opening communication between tubes *g* and *i*, and inasmuch as the measure-tank *B'* was under the assumed condition existing previously to the movement of slide *C* to the right filled with gas under pressure such gas in said measure-cylinder passes therefrom, through said open communication in cylinder *h*, out to the tire-feed nozzle *j*. By reason of the measure-cylinder *B'* having been cut off 90 by said movement of slide *C* toward the right from communication with tube *d* it becomes impossible for the bicyclist during the present condition of the mechanism to obtain any more gas than had been previously passed 95 from tube *d* through the induction-cylinder *e*. The bicyclist continues hold of the handle *G*, so as to maintain slide *C* in its said thrown position toward the right until he has satisfied himself as to the delivery of gas from the 100 tire-feed nozzle. When he is so satisfied, he may let go of handle *G*, whereupon the weight of arm *q* will be sufficient to overcome the inertia of slide *C*, and rock-shaft *D* will thereupon be automatically thrown back to the left 105 into the position shown in Fig. V. Lever *l'* will thereupon be released from cam *o'*, and stem *m'* of the upwardly spring-pressed valve in cylinder *h* will rise, so that said valve in its corresponding rising movement may cut 110 off communication between tubes *g* and *i*, and simultaneously therewith cam *o* will depress lever *l*, which latter will depress stem *m*, thereby causing the upwardly spring-pressed valve in cylinder *e* to be depressed, so as to open 115 communication between tubes *d* and *f*. The eduction means of the measure-cylinder will thereby be cut off, while the induction means of said cylinder will thereby be established in open communication, so that gas under pressure 120 may pass freely into the measure-cylinder and be there retained ready for a repetition of the previously-described operation.

Other modes of applying the principle of my invention may be employed instead of the one explained, change being made as regards the mechanism herein disclosed, provided the means covered by any one of the following claims be employed.

I therefore particularly point out and distinctly claim as my invention—

1. The combination of a fluid-chamber, a fluid-way providing fluid communication between a fluid-supply source and said cham-

- ber and having a valve which controls said communication, a tire-feed device, a fluid-way providing fluid communication between said chamber and said tire-feed device and having a valve which controls said communication, each of said valves having a stem, two levers adapted respectively to engage said two valve-stems, a movable member having cam mechanism adapted to engage said levers, substantially as set forth.
2. The combination of a fluid-chamber, a fluid-way providing fluid communication between a fluid-supply source and said chamber and having a valve which controls said communication, a tire-feed device, a fluid-way providing fluid communication between said chamber and said tire-feed device and having a valve which controls said communication, each of said valves having a stem, two levers adapted respectively to engage said two valve-stems, a slide-bar having cam mechanism adapted to engage said levers, a rock-shaft, engaging mechanism between said shaft and said slide-bar, substantially as set forth.
3. The combination of a fluid-chamber, a fluid-way providing fluid communication between a fluid-supply source and said chamber and having a valve which controls said communication, a tire-feed device, a fluid-way providing fluid communication between said chamber and said tire-feed device and having a valve which controls said communication, each of said two valves having a spring-pressed stem, a rock-shaft having an arm, a slide-bar having means for engaging said arm and also having two cams, two pivotal levers adapted to engage said cams respectively and also said spring-pressed valve-stems respectively, substantially as set forth.
4. The combination of two fluid-chambers, a fluid-way providing fluid communication between said two chambers and having a valve which controls said communication, a fluid-way providing fluid communication between one of said chambers and a point of fluid-delivery and having a valve which controls said communication, each of said valves having a stem, two levers adapted respectively to engage said two valve-stems, a movable member having cam mechanism adapted to engage said levers, substantially as set forth.
5. The combination of two fluid-chambers, a fluid-way providing fluid communication between said two chambers and having a valve which controls said communication, a fluid-way providing fluid communication between one of said chambers and a point of fluid-delivery and having a valve which controls said communication, each of said valves having a stem, two levers adapted respectively to engage said two valve-stems, a slide-bar having cam mechanism adapted to engage said levers, a rock-shaft, engaging means between said shaft and said bar, substantially as set forth.
6. The combination of two fluid-chambers, a fluid-way providing fluid communication between said two chambers and having a valve which controls said communication, a fluid-way providing fluid communication between one of said chambers and a point of fluid-delivery and having a valve which controls said communication, each of said two valves having a spring-pressed stem, a rock-shaft having an arm, a slide-bar having means for engaging said arm and also having two cams, two pivotal levers adapted to engage said cams respectively and also said spring-pressed valve-stems respectively, substantially as set forth.
7. The combination of a fluid-storage chamber, a fluid-measure chamber, a fluid-way providing fluid communication between said two chambers and having a valve which controls said communication, a tire-feed device, a fluid-way providing fluid communication between said fluid-measure chamber and said tire-feed device and having a valve which controls said communication, each of said valves having a stem, two levers adapted respectively to engage said two valve-stems, a movable member having cam mechanism adapted to engage said levers, substantially as set forth.
8. The combination of a fluid-storage chamber, a fluid-measure chamber, a fluid-way providing fluid communication between said two chambers and having a valve which controls said communication, a tire-feed device, a fluid-way providing fluid communication between said fluid-measure chamber and said tire-feed device and having a valve which controls said communication, each of said valves having a stem, two levers adapted respectively to engage said two valve-stems, a slide-bar having cam mechanism adapted to engage said levers, a rock-shaft, engaging means between said shaft and said bar, substantially as set forth.
9. The combination of a fluid-storage chamber, a fluid-measure chamber, a fluid-way providing fluid communication between said two chambers and having a valve which controls said communication, a tire-feed device, a fluid-way providing fluid communication between said fluid-measure chamber and said tire-feed device and having a valve which controls said communication, each of said two valves having a spring-pressed stem, a rock-shaft having an arm, a slide-bar having means for engaging said arm and also having two cams, two pivotal levers adapted to engage said cams respectively and also said spring-pressed valve-stems respectively, substantially as set forth.

Signed by me this 13th day of July, 1900.

JOSEPH H. CHAMP.
